UNITED STATES PATENT OFFICE

RAYMOND K. SHAUINGER, OF BROOKLYN, NEW YORK

DESIGN FOR AN ASH RECEIVER

Application filed January 14, 1932. Serial No. 42,474. Term of patent 7 years.

To all whom it may concern:

Be it known that I, RAYMOND K. SHAUINGER, a citizen of the United States, residing at Brooklyn, in the county of Kings and State of New York, have invented a new, original, and ornamental Design for Ash Receiver, of which the following is a specification, reference being had to the accompanying drawings, forming part thereof.

Fig. 1 is a perspective view of an ash receiver, showing my new design.

Fig. 2 is a plan thereof with a portion broken away.

I claim:

The ornamental design for an ash receiver, as shown.

RAYMOND K. SHAUINGER.
